POCKET INSERT FOR A FILING FOLDER

Rachel Gnader, 4140 Army St.,
San Francisco, Calif. 94120

Continuation-in-part of design application Ser. No. 15,712,
Feb. 10, 1969. This application June 18, 1970, Ser.
No. 23,557

Term of patent 14 years

Int. Cl. D19—99

U.S. Cl. D74—2

FIG. 1.

FIG. 2.

FIG. 3.

FIG. 1 is a front elevational view showing my new design for a pocket insert for a filing folder;

FIG. 2 is a sectional view thereof taken on the line II—II of FIG. 1; and

FIG. 3 is a front perspective view thereof.

This application is a continuation-in-part of my application Ser. No. D. 15,712 filed Feb. 10, 1969, and now abandoned.

I claim:

The ornamental design for a pocket insert for a filing folder, as shown and described.
